UNITED STATES PATENT OFFICE.

LOUIS BOBILLOT, OF BESANCON, FRANCE.

AUTOMATIC FIRE-ALARM.

1,008,370.

Specification of Letters Patent. Patented Nov. 14, 1911.

Application filed December 1, 1909. Serial No. 530,809.

To all whom it may concern:

Be it known that I, LOUIS ROBILLOT, citizen of the Republic of France, residing at No. 6 Square St. Amour, Besançon, France, 5 have invented new and useful Improvements in Automatic Fire-Alarms, of which the following is a specification.

Automatic fire alarms at present employed are usually contrivances dependent upon the 10 expansion of metals or gases under the influence of heat, or upon the ready fusibility of certain fatty substances or metallic alloys. These insulated contrivances, which should be installed in large numbers to afford 15 appreciable security, are connected to electric alarm contrivances, by conductors which may be broken in case of fire, before the alarm devices have performed their function. In addition these contrivances are frequently ineffective by reason of their tardy 20 action.

The present invention has for its object the provision of an alarm which shall afford 25 really efficient protection to premises and buildings against fire, and relates specifically to the construction of the cable employed in devices of this character. This alarm utilizes the destructive action of fire and the expansive actions produced by heat 30 to effect a contact between two insulated electric conductors, situated very near one another, whereof the insulating covering is destroyed almost instantaneously by flames the conductors being constructed and 35 connected to an electric battery, and to electric alarm devices in a manner which will be described by reference to the accompanying drawing in which:—

Figure 1 is a diagrammatic representation 40 of the installation, and:—Figs. 2 and 3 are larger scale views of two examples of construction of a cable carrying bifilar strands which constitute the chief element of this invention. Figs. 4 and 5 are trans- 45 verse sectional views of complete cables of the types illustrated, respectively, in Figs. 2 and 3.

For the purpose of this invention an electric circuit comprises two conductors a , b , 50 insulated from one another, and also insulated at one of their extremities a^1 , b^1 . At their other extremities the two conductors

are connected, the one at b^2 to the positive pole of an electric battery c , the other at a^2 to the negative pole of the same battery 55 through the medium of an indicator d , comprising the local circuit e , f of an electric bell system g . The indicator d and the bell or bells g which are in series, are installed in places chosen so that they are under watch 60 night and day. When any flame reaches the alarm circuit, contact between the two conductors a , b , is brought about by means of the arrangement described above, and the alarm is given. 65

Two return wires h , i , connected to the two wires a , b , of the alarm circuit at their free ends a^1 , b^1 , are led to the place of observation, where they are joined to the two terminals of a junction piece j , k , which allows the 70 effective condition of the circuit and the proper working capability of the alarm contrivance to be tested at any moment. The indicator d has as many indicating surfaces 75 as there are alarm circuits in the establishment to be protected. A separate junction is employed for testing each of the lines.

In consequence of its great flexibility, its strength, its small section and its lightness, the said electric cable alarm lends itself to a 80 multiplicity of combinations, and to very varied applications to installations for protection against fire. It may be applied in various other ways.

The new cable would advantageously be 85 used as a double wire in rooms for all bifilar electric installations of low voltage, especially for telephone and bell installations. The use of this cable, the price of which is very small, would simplify installation and 90 lessen the breakdowns and expenses of upkeep which are considerable items in connection with leads now in use. The two-wire electric cable alarm can be equally well applied to electric apparatus for protection 95 against burglary, since, as said above, the two threads which compose it make contact with one another, and can consequently cause the actuation of a bell, through the medium of an indicator, when the cable is 100 cut by any instrument. One can obtain complete security in respect of this latter application, and also for protection against arson by adopting the following form for

the electric cable alarm:—As shown in transverse section in Fig. 4, on a very much enlarged scale, the new cable is primarily composed of six wires of copper or other metal of a very small diameter, each being covered with a very thin layer of silk thread or other insulating material e' , the wire being twisted together in pairs so as to form three bifilar strands. These three strands are located in three equidistant helical grooves m, n, o , formed in a wire p of copper or other metal, and constituting the safety core of the cable. The cable thus formed is then covered with a thin layer of cotton thread or other soft material d' , and finally with a tube e' of metal of fusible alloy.

The grooves above referred to are of a depth at least as great as, and preferably greater than, the diameter of these twisted strands, the purpose of this construction being to hinder tampering with the strands, but should the strands be molested then owing to the fit thereof in the grooves, and the thin insulation around the strands it would be practically impossible to interfere with one strand without affecting the other and thus giving the alarm. For certain parts of installations, a flexible conductor could under the same conditions be employed, the metallic tubular protector being replaced by a winding of tape.

The six conductors of the cable or of the flexible conductor alarm, distinguished by insulating coverings of different colors could be employed at need, to form one, two or three double wire circuits, of which each wire of the circuit will be composed of one or more elements by connecting in each bifilar strand, one element to one of the threads a of a circuit, and the other element to the second thread b of the circuit (Fig. 2). According to the example above, cable and flexible conductor alarms with two or four strands could also be constructed, by means of one or two strands formed of two insulated conductors twisted together, and located in one or two helical grooves in the metallic safety core. Cables and flexible conductors of the same type could also be formed of eight or even more conductors by varying the number and size of the grooves in the core, and by inserting when needed several bifilar strands in each of these grooves or by employing as a safety core a metallic wire of sufficient cross section to permit of an increase in the number of grooves if and when required.

The alarms described above have the great advantage of being unbreakable by tension, and being incapable of division by any means without the alarm being given. In addition these cables or conductors give

the warning signal very promptly under the action of a flame.

65

The metallic safety core, instead of being formed by a single grooved wire p (Fig. 2) may be constructed, as shown in cross section in Fig. 3, of a plurality of spaced metallic wires r , helically wound on a central metallic wire q , and between which are interposed the bifilar conductors $a-b$ and $h-i$, forming the various electric circuits of the alarm. The auxiliary central and exterior metallic wires q, r , thus employed to form the carrier may be bare or insulated; they may be made of steel, iron, bronze, copper or of any other metal or alloy, but it is advantageous to employ, for this purpose, a metal or alloy of considerable hardness and tensile strength.

By simultaneously winding around the central wire the bifilar strands $a-b, h-i$, and the auxiliary exterior wires r arranged as described above, a cable is obtained of which the strands comprise the auxiliary metallic wires and the bifilar conductor strands interposed. For example in the case of Fig. 3 which is that of an alarm cable of six conductors, there being three bifilar strands, the construction is that of a seven element cable composed of a central auxiliary wire forming a core on which are helically wound three auxiliary wires and three bifilar conducting strands, the latter alternating with the former, that is to say, each of the bifilar strands is interposed between two auxiliary wires. The cable is then covered with a layer of cotton thread or other soft material, d' , and finally with a flexible and fusible metallic tube e' . According to the latter type, cables and flexible conductors could be constructed with two, four, six, eight or even more conductors, the number of the auxiliary exterior wires being varied, and if necessary, a plurality of bifilar strands being located in each of the spaces formed between these wires, or an insulating central wire of a diameter greater than that of the bifilar conducting strands and the auxiliary exterior wires can be employed so as to admit of an increase at need in the number of bifilar conducting strands and auxiliary wires within the periphery of the cable.

It goes without saying that the means of insulation between the wires a, b , which are always close together in the alarm circuit can be varied, and so also can the system of indicators and alarm signals which are interposed in the circuit.

I claim:

A cable of the character described comprising a carrier or support provided with helicoidal grooves therein, a twisted two-strand conductor arranged in each of said

grooves, each strand of each conductor being covered with a thin layer of insulating material and each of said helicoidal grooves being of a depth at least as great as the diameter of the twisted conductor disposed therein.

In testimony whereof I have signed my

name to this specification in the presence of two subscribing witnesses.

LOUIS ROBILLOT.
